A. L. PECK.
COMBINED CHILD'S BED AND EXERCISER.
APPLICATION FILED JUNE 3, 1918.

1,284,438.

Patented Nov. 12, 1918.

UNITED STATES PATENT OFFICE.

ALFRED L. PECK, OF SALT LAKE CITY, UTAH.

COMBINED CHILD'S BED AND EXERCISER.

1,284,438.

Specification of Letters Patent. Patented Nov. 12, 1918.

Application filed June 3, 1918. Serial No. 238,048.

To all whom it may concern:

Be it known that I, ALFRED L. PECK, a citizen of the United States, residing at Salt Lake City, in the county of Salt Lake and 5 State of Utah, have invented certain new and useful Improvements in Combined Children's Beds and Exercisers, of which the following is a specification.

My invention relates to children's beds, 10 and has for its object to provide a child's combination bed and exerciser, which may be used as either when desired.

These objects I accomplish with the device illustrated in the accompanying drawings in 15 which similar letters and numerals of reference indicate like parts throughout the several figures and as described in the specification forming a part of this application and pointed out in the appended claims.

20 In the drawings in which I have shown a substantial embodiment of my invention, Figure 1 is a side elevation of the device as used for an exerciser. Fig. 2 is a vertical longitudinal section of the same. Fig. 3 is 25 a side elevation of the device as used as a bed for a child. Fig. 4 is a rear elevation of the device. Fig. 5 is a plan view of the bed. Fig. 6 is a detail of the exerciser seat.

The present invention consists of a frame 30 within which a child's bed is suspended on springs, and a portion of the bottom of the bed may be turned on its pivot to form the back of a seat and the seat so arranged that the child may take mild exercise by jumping 35 up and down with its feet on the floor. In constructing the invention I provide two spaced apart sills A fastened together by cross pieces B. Two uprights C are vertically secured on said sills A and connected 40 by the cross head B'. The bed rails D are mounted and operated between the said uprights C and supported near one end by the posts E and the other ends by being suspended on the springs 1 and 18. The side 45 pieces F are secured to the said rails D and move therewith.

A portion of the bed bottom consists of a rectangular frame G within which is secured the canvas 2 which takes the place of woven 50 wire and other similar material forming a mattress support. The tension of said canvas 2 may be adjusted by means of the nuts 3 when screwed on the bolts 4. The ends of said canvas are held between the cross ties 5 and said bolts 4 are passed through 55 said cross ties 5. Another portion of the

bed bottom consists of the seat back H which is pivoted between the said side pieces F by the pivot rod 6, and is used as a back for the seat or the portion of the bed bottom as 60 desired. Additional bed rails D' are provided by the links 7 and 8 which are pivoted together and the link 7 pivoted to said rectangular frame G, while the link 8 is pivoted at one end to the side pieces F. 65

A lever link 9 is pivoted and fulcrumed on one side of the device to one of said bed rails D and its lower end is pivoted to a corner of said frame G. A hook 10 is fastened to another cross brace 11 that connects 70 the rear end of said bed rails D, and another hook 12 is fastened to the back of said seat back H. A flexible seat L is provided and carried on the bottom of the said seat back H for use when the baby is old enough to 75 sit up and take moderate exercise, and consists of a piece of flexible material, preferably canvas, shown at L, with portions cut out as at 13 in which the legs of the babe are placed, and with the portion of the flexible 80 seat between said openings 13 provided with straps 14 which portion of said flexible seat is to be fastened across the chest of the baby and over the legs to hold the baby securely in the seat and leave it free to use its legs 85 and arms; and by touching its feet on the floor may jump up and down. The said seat L may be removed for laundering by removing the rods 15 from the hems of the said seat L. The said rods 15 when used 90 to secure the seat L in place, are passed through eye bolts 16 which are fastened in the said side pieces F. The bed frame G and the seat L are both suspended from the rails D, and the said rails D are fulcrumed 95 on a cross rod 17, which in turn is carried in the upper portion of the posts E. The said rails D bear upwardly on the spring 18, and downwardly on the spring 1.

The operation of my invention is as follows:—

When used as a bed, the frame G is released from its engagement with the catch 10 and by throwing the lever link 9 to the position shown in Fig. 3 the said frame G is made to engage with the hook 12 on the back of the seat back H. In making this shift of the bed frame G the links 7 and 8 will change their position, from that shown in Figs. 1 and 2, to that shown in Fig. 3 and 110 form the addition bed rails D'. The mattress, which is to be used on the bed, and is

not shown, is brought into contact with the under side of the flexible seat L, and as said seat is flexible it will not be in the way when the device is so used as a bed. When so shifted and the frame G is made to engage with the seat back H, said back will assume a flatter position as seen in Fig. 3 and the pillow is to be placed on said back H, and the bed is carried with a spring effect by bearing down on the spring 1 and up on the spring 18. When the device is to be used as a jumper or exerciser, the frame G is released from its engagement with the said hook 12 and the lever link 9 is thrown to engage said frame G with the hook 10, and the seat back H is made to assume a nearer perpendicular position, with the additional rails D' also shifted to the link position 7 and 8, as shown in Fig. 2. The baby's legs are placed through the opening 13 and the front portions of said flexible seat L is to be brought up and fastened across the chest of the baby with the straps 14 fastened to the hooks 20 on the inside of the side rails F. As an exerciser and seat for the baby the suspension of the device is from and on the same springs 1 and 18.

Having thus described my invention I desire to secure by Letters Patent and claim:—

1. In a combined bed and exerciser for a small child the combination with two spaced apart sills and uprights and posts thereon, of bed rails fulcrumed on said posts and suspended between said uprights on springs; a bed frame and seat suspended from said rails; and adapted to be shifted for use as a bed or an exerciser as desired; a lever link to effect said shifting; and hooks to engage with said frame and seat to retain them in either position as desired. 30

2. A device of the class described comprising a bed frame suspended on springs; and a seat suspended from the same springs and adapted to be shifted to form a portion of the bottom of the bed or a seat back as desired; and a flexible portion of said seat adapted to sustain a child when in sitting position, and a lever link to shift said bed frame and seat for use as a bed or a seat as desired. 35

In testimony whereof I have affixed my signature.

ALFRED L. PECK.
